UNITED STATES PATENT OFFICE

121,395

DESIGN FOR A DISPLAY BOX OR SIMILAR ARTICLE

Mildred Miller, New York, N. Y.

Application April 23, 1940, Serial No. 91,888

Term of patent 7 years

To all whom it may concern:

Be it known that I, Mildred Miller, a citizen of the United States, residing in the city, county, and State of New York, have invented a new, original, and ornamental Design for a Display Box or Similar Article, of which the following is a specification, reference being had to the accompanying drawing, forming part thereof.

I claim:

The ornamental design for a display box or similar article, as shown.

MILDRED MILLER.
